UNITED STATES PATENT OFFICE.

RICHARD W. POTTER, OF LOWELL, MASSACHUSETTS, ASSIGNOR TO CROMPTON & KNOWLES LOOM WORKS, OF WORCESTER, MASSACHUSETTS, A CORPORATION OF MASSACHUSETTS.

COMBINED SHUTTLE FEELER AND THREAD CUTTER FOR LOOMS.

Application filed March 9, 1925. Serial No. 13,973.

This invention relates to a combined shuttle feeler and thread cutter designed to cut the outgoing weft, as a nearly exhausted weft carrier is ejected from the running shuttle 5 of a weft replenishing automatic loom.

It is the object of my invention to provide a combined shuttle feeler and thread cutter which is exceedingly simple in construction and which is reliable and effective in use.

10 Another object is to provide a thread cutter which is advanced to operative position only when a transfer is about to occur and which is promptly removed to inoperative position if the shuttle fails to be properly boxed.

15 A further object is to provide means for grasping and holding the severed weft end until a temple thread cutter can sever the weft end at the selvage.

20 My invention further relates to arrangements and combinations of parts which will be hereinafter described and more particularly pointed out in the appended claims.

A preferred form of the invention is shown in the drawings in which

25 Fig. 1 is a front elevation of my improved shuttle feeler and thread cutter, the parts being in inoperative or raised position;

Fig. 2 is an end view of certain parts shown in Fig. 1;

30 Fig. 3 is a view similar to Fig. 1, but showing the device in lowered or operative position;

Fig. 4 shows the same parts, after the lay has advanced and opened the cutter;

35 Fig. 5 shows the cutter, after the cutting operation has been performed;

Fig. 6 is a rear view of the shuttle feeler and thread cutter;

40 Fig. 7 is a sectional elevation, taken along the line 7—7 in Fig. 6, and

Fig. 8 is a sectional plan view, taken along the line 8—8 in Fig. 5.

Referring to the drawings, I have shown a shuttle feeler or arm 10 mounted for end-45 wise adjustment on a head 11 which is angularly movable about a pivot 12 on a stand 13 fixed on a magazine frame (not shown). An actuating rod 14 is pivoted at 15 to the head 11 and is moved by actuating devices (not shown) to lower the shuttle feeler 10 into the path of the shuttle S whenever a transfer

is about to occur. The mechanism for thus actuating the rod 14 is well known in the art and forms no part of my present invention.

A lever 16 is pivoted at 17 on the end of the 55 shuttle feeler arm 10 and is connected at its upper end to a rod 18 loosely slidable in a lug 19 on the arm 10. A spring 20 surrounds the rod 18 and maintains the lever 16 yielding in the position shown in Figs. 1 and 3. 60 A cutting or severing member 21 (Fig. 6) is secured to one side face of the lever 16 and has a laterally projecting knife portion 22 which swings past the cutting face of a knife plate 23 which is mounted in a recessed portion of the end of the arm 10. 65

The lever 16 has a laterally projecting clamping portion 25 (Fig. 7) adapted to engage a lug or projection 26 of the arm 10 and clamp the weft end after it is severed by 70 the knife members 22 and 23. The lever 16 also has a downwardly projecting end portion 30 adapted to be engaged by the front edge of the lay 31 as the latter swings forward. The lay 31 is provided with a notch or recess 75 32 for a purpose to be explained.

The arm 10 is provided with a hub 10^a (Fig. 8) through which extends a pin 35 which is fixed in the lever 16 and the outer end of which extends through a close-fitting opening in the cutting member 21. 80

I will now describe the operation of my new shuttle feeler and thread cutter. The parts are shown in Fig. 1 in their normal position, with the thread cutter and clamping device closed and the shuttle feeler raised to 85 inoperative position.

When a transfer is about to occur, the shuttle feeler 10 is swung downward to the position shown in Fig. 3. If the shuttle S is not 90 properly boxed, the end of the shuttle will engage the shuttle feeler 10, swinging the feeler upward to revoke the transfer and simultaneously removing the thread cutter from operative position.

If, however, the shuttle S is properly boxed, the projection 30 of the lever 16 will be engaged by the front edge of the lay and will be swung forward and upward to the position indicated in Fig. 4. At the same time, 100 the thread T is advanced with the shuttle S and is carried into the open jaws of the thread

cutter. As the lay continues to advance, the parts move to the position indicated in Fig. 5, with the projection 30 swinging downward into the recess 32 in the lay, permitting the lever 16 to be moved to close the cutter by the action of the spring 20.

The thread is thus severed by the members 22 and 23 and the severed weft end is grasped by the members 25 and 26 and is held securely 10 until the temple thread cutter can cut the weft end at the selvage. As soon as the weft thread is cut and grasped by the thread cutter, the shuttle feeler or arm 10 is engaged by a fixed part of the lay or the shuttle box and is 15 returned to its initial raised position indicated in Fig. 1, to which position it will remain until another transfer is about to occur.

It will thus appear that my improved shuttle feeler and thread cutter is exceedingly 20 simple in operation, having only a single moving member, and that it is exceedingly reliable, as its single moving member is actuated by direct contact with the lay as the latter moves forward.

Having described my invention and the advantages thereof, it will be evident that changes and modifications can be made therein by those skilled in the art within the spirit and scope of my invention as set forth in the 30 claims, but I do not wish to be otherwise limited to the details herein disclosed.

What I claim is:—

1. In a loom having a lay, a thread cutter having jaws opening at their rear portions, 35 means to open said jaws to receive a thread therein as the lay moves forwardly, means to thereafter close said jaws, and means to remove said thread cutter by a substantially vertical movement from operative position, 40 all during a single continued forward movement of the lay and before rearward movement of the lay begins.

2. In a loom, a shuttle, a lay, a shuttle feeler mounted to swing substantially vertically downward into the path of the shuttle, thread cutting jaws mounted on said feelers and opening rearward, means actuated by the lay to open said jaws on the forward movement of the lay, means to thereafter 50 close said jaws, and means to swing said shuttle feeler and thread cutter substantially vertically upward out of the path of the shuttle during continued forward movement of the lay and before rearward movement there- 55 of begins.

3. In a combined shuttle feeler and thread cutter, a swinging arm, a lay, a shuttle therefor, a pivot for the arm located above and to the rear of the shuttle when the lay is in extreme forward position, a thread cutter, a 60 carrier therefor pivoted on the arm and having a part mounted in fixed relation thereto and engaged by the lay as the latter moves forwardly to open the cutter, and a spring to 65 close said cutter, said arm, carrier, and cut-

ter being thereafter raised to inoperative position above the shuttle during the continued forward movement of the lay.

4. In a thread cutter for looms having a lay and a shuttle, a shuttle feeler movable substantially vertically toward and from shuttle feeling position, a thread cutter mounted on the shuttle feeler and comprising two cutter members relatively movable with respect to each other, an extension 70 mounted in fixed relation to one of the members and positioned in the path of the lay when the shuttle feeler is in shuttle feeling position to be engaged by a part of the lay to cause relative movement of the cutter members to move said members positively to open thread receiving position, and means operative during the continued forward movement of the lay to cause another relative movement of the cutter members to cut the thread 75 and to move said members to closed position, said shuttle feeler being moved substantially vertically as the lay nears its extreme forward position to carry the cutter members 80 out of the path of the shuttle and lay before 85 rearward movement of the lay begins.

5. In a thread cutter for looms having a lay and a shuttle, weft replenishing mechanism, a shuttle feeler pivoted to the replenishing mechanism at a point located above 90 and behind the lay when the latter is in its extreme forward position, a pair of cooperating cutting members on the feeler one of which is movable with respect to the shuttle feeler and having a portion mounted in fixed 100 relation thereto and depending into the path of the lay as the latter moves forwardly and when the shuttle feeler is in lowered shuttle feeling position, said portion being moved by direct engagement with the lay to open 105 the cutting members positively, and means effective during the continued forward movement of the lay to close said cutting members to sever the weft, the shuttle feeler being raised as the lay nears its extreme forward 110 position to carry the cutting members above the path of the shuttle before rearward movement of the lay begins.

6. In a thread cutter for looms having a lay and a shuttle, weft replenishing mechanism, a shuttle feeler pivoted to the replenishing mechanism at a point located above 115 and behind the lay when the latter is in its extreme forward position, a pair of cooperating cutting members on the feeler one of which is movable with respect to the shuttle feeler and having a portion mounted in fixed 120 relation thereto and depending into the path of the lay as the latter moves forwardly and when the shuttle feeler is in lowered shuttle feeling position, said portion being moved by direct engagement with the lay to open 125 the cutting members positively, means effective during the forward movement of the lay to close said cutting members to sever the 130

weft, the shuttle feeler being raised as the lay nears its extreme forward position to carry the cutting members above the path of the shuttle before rearward movement of the

5 lay begins, and a filling thread clamp mounted in part on the shuttle feeler and in part on the cutter member and movable with respect

to the shuttle feeler to hold one end of the thread after the severing operation and to raise the same as the shuttle feeler moves 10 above the path of the shuttle.

In testimony whereof I have hereunto affixed my signature.

RICHARD W. POTTER.
